UNITED STATES PATENT OFFICE.

WILLIAM DANNER, OF SLIDELL, LOUISIANA, ASSIGNOR TO FOREST PRODUCTS CO., A CORPORATION OF LOUISIANA.

APPARATUS FOR THE DISTILLATION OF WOOD.

1,096,687.

Specification of Letters Patent. Patented May 12, 1914.

Application filed September 6, 1912. Serial No. 718,958.

To all whom it may concern:

Be it known that I, WILLIAM DANNER, a citizen of the United States, residing at Slidell, in the parish of St. Tammany and State of Louisiana, have invented new and useful Improvements in Apparatus for the Distillation of Wood, of which the following is a specification.

This invention relates to an apparatus for use in the destructive distillation of wood for the production of turpentine, tar, creosote, commercial charcoal, and like products.

The primary object of the invention is to provide a pair of ovens adapted to have a number of removable retorts mounted therein at different times, and means for heating both ovens and for superheating the steam which is to be used in a certain stage of the process, which process is similar to that described in my prior Patent #883,091, it being understood that the said steam may be supplied by some suitable source which does not form a part of my improved apparatus. In following out the process, the first stage thereof, which is the application of ordinary moist steam to the wood, is carried on first in the retort in one of the ovens, and then after this step is completed, the moist steam is directed into the retort in the other oven and superheated steam is applied to the wood in the first-named retort. These steps or stages of the process take place alternately within the two ovens, and after the wood in any one of the retorts has been sufficiently treated, its retort is removed and another one replaced immediately, so that the operation may take place without interruption, a great deal of time and labor being thus saved.

Another object of the invention is to provide a manifold in the forward end of the retort which has a plurality of perforated pipes attached thereto and projecting into the interior of the retort, so that after the main inlet to the manifold is attached to the feed pipe of the oven, different qualities of steam may be injected into the retort upon adjustment of regulating valves carried by the oven, which control the admission of steam from both the source of moist steam and the superheater into the said feed pipe.

The invention consists of the features of construction, combination and arrangement of parts, hereinafter fully described and

claimed, reference being had to the accompanying drawings, in which:

Figure 1 is a rear elevation of the device. Fig. 2 is a longitudinal vertical sectional view taken on the line 2--2 of Fig. 1. Fig. 3 is a longitudinal horizontal sectional view taken on the line 3--3 of Fig. 1. Fig. 4 is a longitudinal sectional view taken on line 4--4 of Fig. 1 and showing a retort in the oven.

In the drawings, 1 and 2 designate a pair of horizontally spaced, parallel ovens, each comprising a hollow steam cylinder 3 provided at its rear end with a closed head 4. These ovens are set in a casing or jacket 5 of fire brick or some such material, a heating furnace being provided between the ovens. The furnace consists of the fire box 7 and the heating space 8 in which the horizontally disposed superheating coil 9 is disposed, and is inclosed by the side walls 10 and 11, the front and rear walls 12 and 13 and the top wall 14, the rear wall 13 thereof being flush with the rear wall of the casing proper, and the front wall 12 of the furnace being spaced from the front wall of the casing so as to provide a flue 15 therebetween. The products of combustion and the heated air which emanate from the fire box 7 of the furnace are adapted to pass inwardly beneath a horizontal baffle plate 16 which overlies the fire box, upwardly past the front end of the said baffle plate which is spaced from the front end of the furnace, rearwardly through the convolutions of the superheating coil 9 upwardly past the rear edge of a second baffle plate 17 overlying the said coils, then forwardly through the flue 18 provided between the baffle plate 17 and the top wall 14 of the furnace, and down through the flue 15 at the front of the furnace to a point near the bottom of the casing. Lateral openings 19 and 20 are provided at the lower end of the flue 15 in the side walls of the furnace so as to permit the heated gases to pass out into the spaces provided beneath the ovens 1 and 2, respectively, so that the same may be heated by these gases. An upwardly extending flue 23 is provided in the side wall 24 of the casing at the outside of the oven 1 which permits the said gases to pass into a laterally extending, cylindrical jacket 25, which latter extends across the top of the ovens and which is connected to the said flue 23 by

means of the vertical pipe 26 supporting a portion of the jacket 25.

A suitable damper or cut-off valve 27 is provided in the pipe 26 so that the passage 5 of the above-mentioned gases therethrough may be checked whenever desired by the operator. A similar flue 28 is provided in the opposite side wall 29 of the said casing and leads upwardly from the space provided 10 beneath the oven 2 to its connection with the vertical pipe 30, which latter supports and is connected to the previously described jacket 25. A damper 31 is provided in the pipe 30 so as to cut off the passage of gases 15 through the same. A pair of steam supply pipes 32 and 33 are contained within the jacket 25 so that they may be heated by the products of combustion passing from the furnace through one or both of the side flues just described to an extent sufficient to 20 prevent condensation of steam within the pipes while passing to the ovens from a suitable boiler or source of steam located at a point distant from the ovens.

25 A horizontal manifold cylinder 34 is secured to the rear end wall or head 4 of the oven 1, it being provided at its inner end with an annular attaching flange 35 which is provided with a plurality of openings 36 30 which are in alignment with similar openings 37 in the said head 4 and which are intended for a purpose which will be more fully described hereinafter. A vertically extending feed pipe 38 is attached to the manifold 34 at 39 and extends upwardly to a point 40 where it is bent inwardly and extends to its point of attachment 41 with an upwardly and inwardly inclined connecting pipe 42 which is attached to the supply 45 pipe 32 at 43. A hand controlled cut-off valve 44 is connected with the pipe 38 a suitable distance above the manifold 34. A feed pipe 45 is also connected to the manifold 34 and extends upwardly and inwardly 50 toward the front wall of the furnace to a point 46 where it is connected to one protruding end 47 of the superheating coil 9. A hand valve 48 similar to the valve 44 is provided in the vertical portion of the pipe 45 55 immediately above its connection with the manifold. The protruding opposite end 49 of the superheating coil 9 is attached at 50 to a vertically and inwardly extending pipe 51 which is connected at 52 to the supply 55 pipe 33. A regulating valve 53 is connected in the vertical portion of the pipe 51 in rear of the furnace so as to be readily accessible. A manifold cylinder 54 similar to the 60 manifold 34 is attached to the rear end wall 4 of the oven 2 and is provided with an attaching flange 55, on its inner end and closely abutting the said wall or head 5, the said flange having a plurality of horizontal openings therein in alignment with similar 65 openings in the head 4. A feed pipe 57 has

its lower end attached to the manifold 54 and extends vertically therefrom to a point 58 where it is bent inwardly and extends to its point of attachment with the connecting pipe 42, which point is coincident with the 70 point of attachment 41 of the pipe 38. A hand controlled valve 59 is provided in connection with the pipe 57 a suitable distance above the manifold 54. A feed pipe 60 is attached to the manifold 54 and extends upwardly as at 61 for a short distance and then inwardly to its point of connection with the projecting end 47 of the superheating coil 9, a regulating valve 62 being provided in the short vertical portion 61 of 75 this pipe.

A large, vertically extending outlet chamber 63 is mounted upon each of the ovens near the rear end thereof and is in open communication therewith through the opening 64 in the latter. This outlet pipe is intended for the passage of the vaporized products of the distillation and has spaced lateral outlets 65 and 66 which are connected by adjustable valves 65^a and 66^a to 80 suitable conducting pipes, so that the more volatile gases which result from the first process of the distillation may pass off through one of the said branches and the less volatile or more heavy vapors may be moved 85 through the other branch during the second stage of the process, this being regulated by adjustment of the above-described valves. A second outlet chamber 67 extends horizontally from the rear wall or head of each 100 oven at the lower edge thereof, and has spaced, downwardly extending outlets 68 and 69 formed therewith and connected by the adjustable valves 68^a and 69^a to suitable conveying pipes. This second outlet chamber is provided for the passage of rosin and 105 pitch from the oven, the rosin being allowed to pass out through the branch outlet 68 during the first stage of the process, and pitch being afforded an exit through the 110 other branch 69 during the second stage.

The rear end of each oven has an annular attaching member 70 embracing the same and secured in position by suitable means such as riveting or welding, and this member is provided directly above the oven with a pair of spaced lugs 71 between which a hinge block 72 is pivoted by means of a bolt 73. A circular door 74 serving as a closure for the oven, which comprises the 115 annular outer portion 75, the flat central plate 76 secured to the inner face portion 75 and covering the opening 77 therein, and the outwardly bulging outer plate 78 secured to the outer face of the portion 75 120 in registration with the plate 76, is hingedly connected to the annular member 70 through the medium of the hinge block 72, which latter is attached to the portion 75 of the door at its upper edge, as at 79. The air 125

space 80 provided between the plates 76 and 78 of the door serves to prevent radiation of heat from the oven through this end of the same, the body portion of each oven being protected by the casing before described. The annular member 70 is provided in its outer edge with a dove-tailed groove 81 in which is mounted an annular gasket 82 of rubber, or the like, and which is adapted to engage the annular ridge 83 formed on the inner face of the outer portion 75 of the door, to provide an air-tight joint between the door and the oven, the oven being thus hermetically sealed during the time when the retort is positioned therein and the door is closed. The door is secured in closed position by means of the swivel or swing bolts which are pivoted to the member 70 and are received by the marginal notches 84 provided in the outer portion 75 of the door, securing nuts 85 carried by the threaded ends of the side bolts being in engagement with the outer face of the said portion 75 when in this position. Each of the retorts used in the ovens consists of a hollow, cylindrical body 86 which is closed at its front and rear ends by means of the walls 87 and 88, respectively. The retort 86 is provided with a top opening 89 through which wood is admitted to the retort and through which the charcoal residue may be removed, and has a plurality of perforations 90 provided in each side thereof for the escape of the vaporous products of distillation. The retort is mounted upon the flanged wheels 91 which are adapted to run upon a suitable trackway provided without the ovens and adapted to be carried by a track mounted within the oven when the retort is run thereinto or is removed therefrom. The rails 92 which comprise the track within each of the ovens are formed of angle iron, which latter consist of a horizontal bearing portion and the vertical inner portion. The bearing portion is adapted to be positioned upon a plurality of spaced, horizontally extending, supporting brackets 95, a plurality of spaced vertical brackets 96 engaging the inner face of the vertical portion of each rail so as to maintain the same firmly in position. The rails 92 may be secured to the brackets in any suitable manner or may rest in position without being fastened in position so that they may be removed in order to facilitate the cleaning of the oven. Bands 97 and 98 embrace the front and rear ends of the retort and are provided with annular flanges 99 and 100, respectively, which are adapted to bear against any surface with which the retort may come in contact so as to support or protect the same. An outlet opening 101 is provided in the bottom of the retort at its inner end as an exhaust for the rosin or pitch and is disposed so that it may pour

into the outlet chamber 67 carried by either of the ovens.

Each retort has an oblong manifold 102 secured within the same against the rear wall thereof so that its reduced circular outer portion 103 extends through an opening 104 in the said wall. The body portion of the manifold which is located interiorly with respect to the retort has its inner and side walls provided with a plurality of threaded pipe openings 105 into which are threaded the perforated pipes 106 which are adapted to inject either ordinary live steam or superheated steam to the contents of the retort. The interior space 107 of the manifold is in communication with an outwardly extending opening 108 which passes through the reduced portion 103. The portion 103 is still further reduced, as at 109, to form a trunnion for the retort, this portion being provided outwardly with an attaching flange 110 having a plurality of attaching studs 111 provided thereon and extending outwardly therefrom. When the retort is mounted within either of the ovens, the flange 110 engages with the rear wall or head of the oven so that the studs 111 are received by the openings 36 in the flange 35 of the feed chamber 34, and the opening 108 is in communication with the opening 112 provided in the head of the oven and opening into the chamber 34. When securing nuts 113 have been threaded on the outwardly protruding ends of the studs 111 and have been properly tightened, a steam-tight joint is effected, so that steam may be admitted through the said openings and manifold into the interior of the retort. A coacting trunnion 114 is attached in suitable manner to the front wall of the retort in direct horizontal alignment with the trunnion thus afforded by the manifold, so that the retort may be suspended from these trunnions by a suitable support or bearing after it has been removed from the oven within which it has been used, and may be rotated when in this position in order to remove the residue from the retort by the aid of gravity, through the top opening 89. In carrying out my process with the improved apparatus described herein, the wood to be used in the retorts is cut into the desired size and is inserted into one of the retorts through its top opening. The retort is then run along the trackway provided therefor and is inserted within the oven designated by the numeral 1, for instance, and the attaching flange carried by the manifold on the retort is secured in the above described manner to the head of the oven. After the oven door has been secured in its closed position and the valves 66 and 68 have been opened, ordinary live steam is injected into the retort by opening the valve 44. This steam passes through pipes 32, 42,

and 38, into the manifold 34, from which it enters the retort through manifold 102 and the perforated pipes 106. In this manner the more volatile products such as turpentine and the like are driven off in the form of light vapor through the outlet chamber 64 and the branch outlet 66 to suitable receptacles provided therefor. The liquefied rosin during this stage of the process passes out through the outlet chamber 67 and the branch 68, after this operation has continued for a proper length of time necessary to remove all of the products which become volatile at the temperature of the injected steam. In the meantime a second retort has been inserted in oven 2 and is ready to have steam injected into it. When the stage just described, of the process, has been completed, the valve 44 is closed so as to cut off the steam, and the outlet valves 66^a and 68^a of the first oven are closed and the valves 65^a and 69^a of the same oven are opened. The valves 66^a and 68^a carried by the second oven are then opened, the valve 59 in the steam feed pipe is opened so as to admit ordinary live steam to the retort carried by the second oven. After the steam has been superheated in the furnace, the valve 48 is opened so as to admit superheated steam into the retort within the first oven through pipe 45 and the previously-described manifolds. During this operation the heavier vapors are driven off through the outlet chamber 64 and the branch outlet 65, and the pitch which runs out through the opening 101 in the bottom of the retort passes out through the outlet chamber 67 and the branch outlet 69. After the second stage of the process has been undergone in the first oven and the first stage has been concluded in the second oven, the retort within the first oven is withdrawn and another retort replaces it therein, after the valve 48 and the outlet valves have been closed. The valve 59 is now closed and the outlet valves 66^a and 68^a carried by the second oven are closed, and the valves 65^a and 69^a carried thereby are opened. The valve 62 is then opened so as to admit superheated steam to the retort in the second oven, and the second stage of the process therein is commenced. These alternate operations are repeated again and again with comparatively no loss of time, splendid results being accomplished with a minimum cost of fuel due to the economical use of heat as ren-

dered possible by the apparatus which I have provided.

What is claimed is:

1. In a distilling apparatus, the combination of a pair of ovens disposed adjacent to each other, a feed chamber mounted exteriorly upon each oven, the said oven having an opening in one of its walls in communication with the chamber, retorts adapted to be positioned within the ovens, a manifold provided upon each retort in communication with the interior thereof and having an opening adapted to register with the said oven opening, a source of supply of ordinary live steam, a supply pipe extending from said source to a point adjacent to the said ovens, branch pipes connecting the said supply pipe with the respective oven feed chambers, an adjustable valve provided within each of said branch pipes, a source of supply of superheated steam, a supply pipe connected with the said source, branch pipes connecting the last-named supply pipe with the said feed chambers, and an adjustable valve provided in each of the last-named branch pipes.

2. In a distilling apparatus, an oven having an opening in one of its walls, a feed chamber mounted exteriorly upon the wall of the oven in communication with the said opening, a flange provided upon the said chamber having a plurality of openings therein, the said wall of the oven being provided with openings surrounding its first-named opening in communication with the flange openings, a retort adapted to be mounted within said oven, a manifold mounted upon the retort in communication with the interior thereof and having a head adapted to abut the said wall of the oven, the said head being provided with a main opening adapted to register with the first-named opening of the oven wall, a plurality of attaching bolt members formed upon the said head of the retort manifold and being adapted for engagement within the registering openings of the oven wall and flange of the feed chamber so as to project outwardly therethrough, and securing nuts for the outer end of the said bolt members.

In testimony whereof I affix my signature in presence of two witnesses.

WILLIAM DANNER.
